DESIGN FOR AN ELECTRIC HOT WATER HEATER

Harry A. Rush, Los Angeles, Calif.

Application March 23, 1940, Serial No. 91,188

Term of patent 14 years

To all whom it may concern:

Be it known that I, Harry A. Rush, a citizen of the United States, residing at Los Angeles, in the county of Los Angeles and State of California, have invented a new, original, and ornamental Design for an Electric Hot Water Heater, of which the following is a specification, reference being had to the accompanying drawing, forming part thereof.

The figure is a perspective view of an electric hot water heater, showing my new design.

The other side of the heater is substantially like the side shown except the handle portion is omitted.

I claim:

The ornamental design for an electric hot water heater, as shown and described.

HARRY A. RUSH.
